UNITED STATES PATENT OFFICE

117,149

DESIGN FOR A CHANGEABLE EXHIBITOR

Jacob I. Robin, New York, N. Y., assignor to International Mutoscope Reel Co. Inc., New York, N. Y., a corporation of New York

Application February 7, 1939, Serial No. 82,821

Term of patent 7 years

To all whom it may concern:

Be it known that I, Jacob I. Robin, a citizen of the United States, residing at New York, in the county and State of New York, have invented a new, original, and ornamental Design for a Changeable Exhibitor, of which the following is a specification, reference being had to the accompanying drawing, forming a part thereof.

Fig. 1 is a front elevational view of a changeable exhibitor showing my new design.

Fig. 2 is a top plan view thereof.

Fig. 3 is a side elevational view thereof.

I claim:

The ornamental design for a changeable exhibitor, as shown.

JACOB I. ROBIN.
